UNITED STATES PATENT OFFICE.

HIPPOLYTE JEAN MARIE PIERRE LA BASTIDE, OF LIMOGES, FRANCE, AS-SIGNOR TO THE SOCIÉTÉ LA CÉRAMIQUE J. POUYAT, OF SAME PLACE.

DESIGN FOR A DISH.

SPECIFICATION forming part of Design No. 24,786, dated October 22, 1895.

Application filed May 15, 1895. Serial No. 549,443. Term of patent 7 years.

To all whom it may concern:

Be it known that I, HIPPOLYTE JEAN MARIE PIERRE LA BASTIDE, L'Administrateur délégué de la Maison J. Pouyat, a citizen of the 5 Republic of France, residing at Limoges, in the Department of Haute Vienne, in the Republic of France, have invented and produced a new and original Design for Covered and other Dishes, of which the following is a specification, reference being had to the accompanying drawing, forming a part thereof, in which a portion of the top and likewise one side of a covered dish are represented, in which the new design is embodied.

10 The leading feature of the design consists in the handle for the cover A and the handles and base for the body B. The handles of both the body and cover are substantially the same in contour, each involving a curled-leaf figure a and a curved-stem figure a', which meets one end of the leaf figure. The base is 15 apparently a continuation of the body, and the lower edge of the base is convolved in such manner that the body of the dish is apparently supported by claw-legs b interposed by

curved panels b'. The cover A and body B in their general contour are given what is known as the "Lafayette shape." The minor features of the design consist of the surface decorations of the cover and the body. Embossed leaves c are arranged around the base of the handle for the cover, and adjacent to the margin of the cover groups of leaf scrolls, apparently embossed and arranged in reverse order, appear on the top of the cover. 30 The body adjacent to the handles is decorated with leaf figures e of the scroll order, and pendent leaf figures e' are located between, thus decorating the surface of the body of the handle, all of the body and surface decorations above alluded to being apparently embossed.

I claim—

The design for covered dish herein shown and described.

HIPPOLYTE JEAN MARIE PIERRE LA BASTIDE.
